(57) **ABSTRACT**

A new clementine tree named 'Early Esbal' characterized by its early-maturing fruit.

6 Drawing Sheets

1

Latin name: *Citrus x clementina*.

Common name: Clementine.

Variety denomination: 'Early Esbal'.

BACKGROUND AND SUMMARY OF THE VARIETY

'Early Esbal' is a new clementine tree, originally discovered in a cultivated area near Citrusdal, WC, Republic of South Africa during the 2008/2009 growing season, as a spontaneous bud sport mutation of the 'Eabal' clementine variety (not patented). The 'Early Esbal' tree was first noticed because its fruit was coloring sooner than the fruit on surrounding 'Eabal' trees. Upon continued observation, the fruit was found to mature about 3 weeks earlier than 'Eabal'. The new variety was asexually propagated by grafting in 2011 at Citrusdal, Western Cape, Republic of South Africa, and has since been found to remain true to type over successive asexually propagated generations.

'Early Esbal' is distinguishable from parent variety 'Eabal' by its early maturity. 'Early Esbal' is distinguishable from similar variety 'Nules' (also known as 'Clemenules', not patented) by its early color development up to 2 weeks before 'Nules' and by its elongated fruit and the absence of parthenocarpy.

BRIEF DESCRIPTION OF THE PHOTOGRAPHS

The accompanying photographs were taken in 2019 and 2020 at Visalia, Calif. The trees depicted were topworked in 2018. The colors of the claimed variety may vary with lighting conditions. Color characteristics of the variety should therefore be determined with reference to the observations described herein, rather than from these illustrations alone.

FIG. 1 shows an 'Early Esbal' clementine tree;

FIG. 2 shows 'Early Esbal' leaves;

FIG. 3 shows buds and blossoms from an 'Early Esbal' tree;

FIG. 4 shows whole and sectioned 'Early Esbal' fruit;

2

FIG. 5 shows 'Nules' fruit (top) and 'Early Esbal' fruit (bottom); and,

FIG. 6 shows photos taken the same day of fully colored 'Early Esbal' fruit (left) and 'Nules' fruit (right).

DETAILED BOTANICAL DESCRIPTION

The following detailed botanical description is based on observations recorded at Visalia, Calif. in 2019 and 2020. 10 The trees described were topworked in 2018 onto 'Carrizo' rootstock (not patented). The characteristics described will vary somewhat depending upon cultural practices, climatic conditions, location and growing season. Quantified measurements are expressed as an average of measurements 15 taken from a number of individual plants of the claimed variety. The measurements of any individual plant or any group of plants of the variety may vary from the stated average. Colors are described with reference to The Royal Horticultural Society Colour Chart (5th Ed., v.2).

DETAILED BOTANICAL DESCRIPTION

Tree:

Vigor.—Medium.

Density of canopy.—Medium.

Habit.—Upright.

Height.—150 cm to 190 cm.

Spread.—110 cm to 140 cm.

Trunk diameter (at 30 cm above the graft).—4.5 cm to 4.75 cm.

Bark texture.—Smooth.

Bark color.—Grey-brown 199D.

Tendency toward alternate bearing.—None.

Chilling requirement.—None.

Branch:

Length.—76 cm.

Diameter.—1 cm.

Crotch angle.—Narrow to medium.

Bark color.—Young wood yellow-green 144B; mature wood grey-brown 199D.

Bark texture.—Smooth.

<i>Thorns.</i> —Very few to none.		<i>Leaf shape.</i> —Elliptic.
<i>Current year shoot length.</i> —10 cm.		<i>Apex shape.</i> —Acute.
<i>Current year shoot color.</i> —Yellow-green 149B.		<i>Base shape.</i> —Cuneate, aequilateral.
Flowers:		<i>Venation.</i> —Pinnate.
<i>Bud shape.</i> —Pyriform.	5	<i>Arrangement.</i> —Alternate.
<i>Bud length.</i> —0.5 cm to 1.25 cm.		<i>Color of upper surface.</i> —Green 143A.
<i>Bud diameter.</i> —0.5 cm to 0.5 cm.		<i>Color of lower surface.</i> —Yellow-green N144B.
<i>Bud color.</i> —White NN155B.		<i>Vein color.</i> —Green 143C.
<i>Quantity of blossoms per cluster.</i> —3 to 5.	10	<i>Petiole length.</i> —1.5 cm to 2.0 cm.
<i>Relative position of petal margins.</i> —Not touching.		<i>Petiole diameter.</i> —2.5 mm.
<i>Blossom diameter.</i> —2.7 cm.		<i>Petiole color.</i> —Green 143A.
<i>Blossom depth.</i> —0.5 cm.		<i>Wings.</i> —Not present.
<i>Pollen.</i> —Yellow 8C.		Fruit:
<i>Sepal length.</i> —3 mm.		<i>Quantity per cluster.</i> —3.
<i>Sepal width.</i> —1.5 mm to 2 mm.	15	<i>Axial diameter.</i> —5.2 cm.
<i>Sepal shape.</i> —Acuminate.		<i>Apical diameter.</i> —4.5 cm.
<i>Sepal margin.</i> —Entire.		<i>Weight.</i> —60 to 65 g.
<i>Sepal color—upper surface.</i> —Yellow-green 150C.		<i>General shape in profile.</i> —Round.
<i>Sepal color—lower surface.</i> —Yellow-green 150C.		<i>Position of maximum diameter.</i> —Equator.
<i>Quantity of petals per flower.</i> —5.	20	<i>Navel.</i> —Present.
<i>Petal shape.</i> —Lanceolate.		<i>Rind color.</i> —Orange 28B.
<i>Petal apex.</i> —Acute.		<i>Oil gland diameter.</i> —1.0 mm to 1.5 mm.
<i>Petal margin.</i> —Entire.		<i>Oil gland density.</i> —4 to 6 per cm ² .
<i>Petal length.</i> —1.0 cm to 1.25 cm.	25	<i>Rind thickness.</i> —2 mm.
<i>Petal width.</i> —0.5 cm to 0.6 cm.		<i>Ease of peeling.</i> —Easy.
<i>Petal color—upper surface.</i> —White NN155B.		<i>Rind texture.</i> —Smooth to somewhat pebbly.
<i>Petal color—lower surface.</i> —White NN155A.		<i>Albedo thickness.</i> —1.5 mm.
<i>Pedicel length.</i> —0.7 cm.		<i>Quantity of fruit segments per fruit.</i> —10.
<i>Pedicel diameter.</i> —1 mm to 2 mm.	30	<i>Toughness of segment membrane.</i> —Soft.
<i>Pedicel color.</i> —Yellow-green N144B.		<i>Segment length.</i> —3.8 cm.
<i>Pistil quantity per flower.</i> —14 to 15.		<i>Segment diameter.</i> —2.0 cm.
<i>Pistil length.</i> —0.9 cm to 1.2 cm.		<i>Juice sac length.</i> —9 mm to 11 mm.
<i>Pistil color.</i> —Yellow-green 145C.		<i>Juice sac shape.</i> —Elongated.
<i>Stigma length.</i> —2 mm.	35	<i>Juice sac color.</i> —Orange 23B.
<i>Stigma color.</i> —Yellow-green 153D.		<i>Juice soluble solids.</i> —10.1° Brix.
<i>Style length.</i> —0.8 cm to 1.0 cm.		<i>Relative harvest maturity.</i> —Early.
<i>Style color.</i> —White NN155B.		<i>Harvest begins.</i> —Mid- to late October.
<i>Ovary length.</i> —4 mm.	40	<i>Seeds.</i> —None (trees netted during flowering).
<i>Ovary diameter.</i> —3.5 mm.		<i>Stem length.</i> —5 mm.
<i>Ovary color.</i> —Green 143B.		<i>Stem diameter.</i> —3 mm.
<i>Anther quantity per flower.</i> —14 to 15.		<i>Stem color.</i> —Yellow-green N144B.
<i>Anther length.</i> —2.0 to 2.5.		<i>Harvest yield.</i> —35 to 50 metric tons/hectare.
<i>Anther color.</i> —Yellow-green 154B.		<i>Market use.</i> —Fresh, domestic and export.
<i>Date of first bloom.</i> —April 10 (2020 growing season).	45	<i>Keeping quality.</i> —Good.
<i>Date of full bloom.</i> —April 20 (2020 growing season).		<i>Pest and disease resistance.</i> —None noted.
<i>Date of first fruitlet fall.</i> —May 15 (2020 growing season).		<i>Pest and disease susceptibility.</i> —None noted.
<i>Pollenizer.</i> —Not required.		<i>Winter hardiness.</i> —Unknown.
Leaves:		<i>Drought and heat tolerance.</i> —Unknown.
<i>Length.</i> —9 cm to 11 cm.	50	I claim:
<i>Width.</i> —4.0 cm to 4.75 cm.		1. A new and distinct variety of clementine tree substantially as described and illustrated herein.
<i>Length/width ratio.</i> —About 2.25:1.		* * * * *
<i>Blade margin.</i> —Entire.
